CLAIM

The ornamental design for an electronic cable, as shown and described.

DESCRIPTION

FIG. 1 is a front view of an electronic cable, showing our new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a top left front perspective view thereof.

FIG. 8 is a bottom-right-front perspective view thereof.

FIG. 9 is a bottom-left-rear perspective view thereof.

FIG. 10 is a top-right-rear perspective view thereof.

FIG. 11 is an enlarged top-left-front perspective view of a front end of the electronic cable, indicated by "11" in FIG. 7; and,

FIG. 12 is an enlarged top-right-rear perspective view of a rear end of the electronic cable, indicated by "12" in FIG. 10. The broken lines in the drawings are for the purpose of illustrating portions of the electronic cable that form no part of the claimed design.

The electronic cable is shown with a symbolic break in its length. The appearance of any portion of the electronic cable between the break lines forms no part of the claimed design.
